CENTRAL ELECTRIC COMPANY, OF CHICAGO, ILLINOIS, A CORPORATION OF
ILLINOIS.

ELECTRIC SWITCH.

1,188,438.

Specification of Letters Patent. Patented June 27, 1916.

Application filed April 8, 1914. Serial No. 830,379.

To all whom it may concern:

Be it known that we, GEORGE GOLDMAN and GUY F. STURGEON, citizens of the United States of America, and residents of Chicago, Cook county, Illinois, have invented a certain new and useful Improvement in Electric Switches, of which the following is a specification.

Our invention relates to an improvement 10 in electric switches and particularly to a switch which is adapted for use in connection with electric lighting systems.

In electric lighting systems, and especially in street car lighting systems, it is 15 customary to connect a plurality of lights in series across the power circuit and if any one of these lights burn out the circuit for the remaining lights is broken and all lights in the series are rendered inoperative. 20 This, of course, is very objectionable and becomes especially so in systems where but a single lighting unit is employed—that is, where a car is illuminated by means of but one group of lights connected across the 25 power circuit in series.

The object of our invention is to provide a switch which can be operated either manually or automatically to shunt out any light whose circuit becomes broken, and by so 30 doing prevent the other lights of the series from being rendered inoperative.

By our invention also we contemplate the provision of a switch by which any two lights, or even three lights, can be shunted. 35 Thus supposing we have a series of five lights and two of these—the first and third—burned out; by properly operating our switch a shunt circuit could be closed around these first and third lights so that 40 the remaining three lights would remain in operative condition.

Our invention will be more readily understood by having reference to the accompanying drawings, in which we have illustrated one specific embodiment of our invention.

Figure 1 represents a plan view, partly in section, of a switch embodying the features of our invention. Fig. 2 is a front view 50 partly in section of the switch. Fig. 3 is a sectional view taken on the line 3—3 of Fig. 2, looking in the direction of the arrows. Fig. 4 is a circuit diagram showing the manner in which the switch is electrically connected with the lighting circuit. 55

Fig. 5 is a circuit diagram showing the manner in which the switch can be adapted for two series of lights. Fig. 6 is a diagrammatic view showing the manner in which the switch may be operated automatically. 60

Referring to Figs. 1, 2 and 3, we have there shown a rectangular box-like casing 11 provided with a cover 12, which cover is provided with an elongated slot 13. 65 Within this box is located a block 14 which carries a series of contacts 15 arranged along one side of said block. Also mounted on this block are two series of contact strips 16 and 17. A rider 18 is provided having 70 depending arms 19 which engage in grooves in the side of the block, which rider carries a pair of contacts 20—21, which are adapted to engage with the contacts 15 on the contact plug, which contacts 20—21 are 75 connected by a resistance 22. This rider also carries a contact 23 adapted to engage with the metallic strips 16 on the contact plug, and a contact 24 adapted to be engaged with the metallic strips 17. These 80 two contacts 23—24 are likewise spanned by a resistance 25. The rider is provided with an upwardly extending stem 26 which projects through the slot 13 in the cover, which stem is provided with a knob 27 by 85 which means this rider can be moved back and forth over the contacts carried by the block 14.

Referring now to Fig. 4, we have there shown the manner in which these various 90 contacts are electrically connected to the conductors 28 of the lighting circuit, in which circuit are included a plurality of lamps L', L², L³, L⁴, L⁵. It will be seen that the first contact 15 is connected to the lighting circuit on one side of these lights, and the second contact is connected between the lights L', L², and the third contact between the lights L², L³, etc., until the sixth contact is reached, which is connected to the conductor 28 beyond the light L⁵. Considering 95 these six contacts and the rider carrying the two contacts 20—21, it will be seen that by moving this rider so that these two contacts engage with various pairs of the contacts 100 15, that any one of the lights L' to L⁵ can be shunted by the resistance 22. Thus consider that the light L⁴ burned out, it will merely be necessary to move this rider so that the contacts 20—21 engage the contacts 105 110

15 connected on opposite sides of this light L^4 , and then the circuit will be completed through the other remaining four lights, this circuit passing through the shunt resistance 22. This resistance is preferably substantially equal to the resistance of one of the lights, so that when such resistance is substituted for one of the lights, the total resistance of the series across the lighting circuit remains unchanged and thus the amount of current passing through the remaining lights remain unchanged. If it is desired to only shunt out any one of these lights, then only these six contacts would be necessary in the switch. However, in order to provide means whereby any combination of two of the lights can be shunted out, we have added further contacts 15, together with the strips 16, the first of which is connected to a point between the lights L' and L^2 , while the second of which is connected to a point between the lights L^3 and L^4 . The strips 17 are likewise wired up in the manner indicated, as are the additional contacts 15. With this construction, it will be seen that by properly moving the rider, any combination of two of the lights can be shunted out so that the resistances 22—25 are shunted across each of these two lights. If desired, this development can be continued so as to provide for the shunting of any combination of three or more of the lights, but it would hardly ever be necessary in practice to provide for more than two lights burning out at a time, and in fact often times it would not be necessary to provide for even this contingency, as it would be very seldom that more than one light would burn out before opportunity would be found for replacing this light with a new one.

In Fig. 5, we have shown a circuit arrangement by which my invention is adapted to be used so as to shunt out a light in either one of two series. The construction of the switch can be substantially the same except that the two contacts 20—21^a, carried by the rider, travel over separate series of contacts 15^a which contacts are connected in the manner indicated, so that by properly positioning the rider, any one of the lights in either of these two series can be shunted by the resistance 22^a.

In Fig. 6, we have shown means whereby the rider 18^a, carrying the contacts 20^a—21^a, can be operated automatically when any light burns out. In order to accomplish this, we provide a pivoted lever 29 to the long arm of which the rider 18^a is attached, the shorter arm being connected to the upper end of the plunger 30 of a solenoid which comprises two windings, one winding 31 of which is bridged directly across the lighting circuit 28, while the other winding 32 is connected in series with this lighting circuit. These two windings are connected differ-

tially, and, therefore, when the current flows through the circuit 28, the magnetization produced by the two windings of the solenoid tend to neutralize each other and the solenoid plunger 30 is not operated. If, however, one of the lights L burns out, the circuit through the winding 32 is broken and thus the winding 31 operates to energize the solenoid which draws the rider upward over the contacts 15^a until the contacts 20^a—21^a span the light which is burned out. The circuit through the other winding 32 is then completed through the resistance 22^a, and the solenoid is again rendered inoperative and the rider remains in this position. When the burned out lamp is replaced, it is merely necessary to manually move the rider back to its normal position.

It will thus be seen that we have devised a very simple and efficient switch for shunting out any one of the lights of a series, but while we have shown one specific embodiment of our invention, it will, of course, be understood that various changes and modifications can be made without departing from the spirit of our invention and that we do not wish to be limited to the particular construction of switch which we have shown, this construction being shown merely for the purpose of illustrating one manner in which our invention may be carried out.

What we claim as our invention is:

1. In an apparatus of the class described, an electrical circuit, a plurality of lights in said circuit, a switch, a resistance, and means for operating said switch to cause said resistance to shunt any one of said lights. 100
2. In an apparatus of the class described, an electrical circuit including a plurality of lights, a switch including a pair of movable contacts connected by a resistance, said movable contacts adapted to engage various pairs of said stationary contacts to thereby shunt out any one of said lights. 105
3. In an apparatus of the class described, an electrical circuit including a plurality of lights connected in series, a pair of contacts connected to opposite sides of each of said lights, a rider carrying a pair of contacts adapted to engage successively said first-mentioned pairs of contacts, a resistance connected between said contacts carried by said rider, whereby said rider may be moved so as to cause said resistance to be connected 115 in shunt of any one of said lights. 110
4. In an apparatus of the class described, an electrical circuit, a plurality of lights connected in series in said circuit, a resistance, and means for automatically connecting said resistance in shunt of any one of said lights. 125
5. In an apparatus of the class described, an electrical circuit, a plurality of lights connected in series in said circuit, a resist- 130

ance, and means controlled by the breaking of the circuit through any light for automatically causing said resistance to be connected in shunt of said light.

5. In an apparatus of the class described, a plurality of lights connected in series in said circuit, a series of contacts associated with said lights, a resistance, and means including a solenoid magnet for moving said 10 resistance over said contacts to shunt out any one of said lights.

7. In an apparatus of the class described, a plurality of lights connected in series in said circuit, a series of contacts associated 15 with said lights, a resistance, means including a solenoid magnet for moving said resistance over said contacts to shunt out any one of said lights, and means controlled by the breaking of the circuit in any one of 20 said lights for causing the operation of said magnet.

8. In an apparatus of the class described,

an electrical circuit including a plurality of lights connected in series, contacts associated with said lights, a resistance adapted 25 to be connected in shunt with any pair of said contacts, means including a solenoid magnet for moving said resistance over said contacts, a pair of differential windings for said solenoid, one of said windings being 30 bridged across said circuit, the other of said windings being connected in series with said circuit, whereby when the circuit in any one of said lights is broken said solenoid will be operatively energized to move said resistance so as to shunt said light. 35

Signed by us at Chicago, Illinois, this second day of April, 1914.
